LLP(57) **CLAIM**

The ornamental design for a motor vehicle fascia, as shown and described.

DESCRIPTION

FIG. 1 is an isometric view of a motor vehicle fascia;
FIG. 2 is a side elevational view, the opposite side being a minor image thereof;
FIG. 3 is a front elevational view;
FIG. 4 is a top plan view; and,
FIG. 5 is a bottom plan view.
The broken lines in the figures depict portions of the invention that form no part of the claimed design.
